UNITED STATES PATENT OFFICE.

BERNARD R. WEIR, OF MUSKEGON, MICHIGAN, ASSIGNOR TO QUALITY ALUMINUM CASTING COMPANY, OF MUSKEGON HEIGHTS, MICHIGAN, A CORPORATION OF MICHIGAN.

DESIGN FOR A GRAVE MARKER.

Application filed July 31, 1922. Serial No. 3,252. Term of patent 7 years.

To all whom it may concern:

Be it known that I, BERNARD R. WEIR, a citizen of the United States, residing at Muskegon, in the county of Muskegon and State of Michigan, have invented a new, original, and ornamental Design for Grave Marker, of which the following is a specification, reference being had to the accompanying drawing, forming part thereof.

In the drawing:

The figure is a view in perspective of the grave marker of my design.

I claim:

The ornamental design for grave marker as shown.

In witness whereof, I hereunto subscribe my name this 18 day of July, 1922.

BERNARD R. WEIR.

Witnesses:

GEORGE H. STEVENS,
ARTHUR W. CARLSON.
